FLASHLIGHT FOUNTAIN PEN

Herbert Gudge, New York, N. Y.

Application June 22, 1938, Serial No. 215,120

2 Claims. (Cl. 240—6.46)

The purpose of this invention is to provide a relatively small light in a fountain pen, in which the pen casing is so constructed that it may readily be opened providing access to the pen sack and also to the battery.

The invention is a fountain pen having a split casing hinged along one side so that it may be opened, and in which the casing is provided with a small battery and also an ink reservoir or sack, with means feeding ink to the nib of a pen, and also with means mounting a relatively small flashlight in an enclosed tip of the casing adjacent the nib.

Fountain pens have been provided with flashlights, however, these have been made comparatively cumbersome, with the lights and batteries on the sides, or with one placed above the other, and, with any construction up to the present time, the interior of the device is comparatively inaccessible.

The object of the invention is, therefore, to provide a fountain pen of the type having a light adjacent the nib, in which the casing may readily be opened so that the interior parts are readily accessible.

Another object is to provide a fountain pen having a light adjacent the nib, in which a battery for the light and also the ink sack are positioned in the casing with one on one side and the other on the other.

Another object of the invention is to provide a fountain pen with a relatively small window through which one may determine when the pen is empty.

A further object is to provide a fountain pen having a light adjacent the nib, in which the light is embodied within the pen casing.

And a still further object is to provide an improved fountain pen having a light in combination which is of a simple and economical construction.

With these ends in view the invention embodies a fountain pen having a light adjacent the nib, in which the pen casing is hinged longitudinally, with the ink sack in one side, a battery in the other, and in which the end of the casing is made transparent, with the nib mounted in the transparent end, and also with a relatively small light in said transparent end.

Other features and advantages of the invention will appear from the following description taken in connection with the drawing, wherein:

Figure 1 is a view showing a side elevation of the device with parts broken away.

Figure 2 is a cross section through the casing

of the pen, showing the relative positions of the parts and showing an alternate construction in which the casing or body of the pen is formed of two halves hinged together.

5 Figure 3 is a similar section on line 3—3 of Figure 1 with the cap omitted.

In the drawing the device is shown as it may be made, wherein numeral 1 indicates the pen casing, numeral 2, the cap, and numeral 3, a light.

10 The casing 1 is substantially the same size as a fountain pen of the usual type, or a trifle larger, and this is formed in two halves 4 and 5 hinged together at the point 6, and held together by a snap 7. The snap is provided with a button 8, and it will be noted that, as the button is pressed inward, it will release the snap and make it possible to open the casing.

The ink sack 9 in the design shown in Figure 2 is 15 mounted in the part 4 of the casing, and this is connected to an opening 10 that extends through a transparent member 11 at the end of the casing and in which the nib 12 is mounted, and the pen may be refilled by a button 13 at the opposite end, similar to pens now in use. It will be

20 understood that any suitable mechanism may be used inside of the pen body to compress and inflate the ink sack. In the opposite half of the casing is a battery 14, and spring fingers 15 and 16 are slidably mounted on the battery through a ring 17, and the ring is provided with a strip 18 that extends backward and through an opening 19 in the casing, with the end of the strip bent over to form a clip 20 similar to any clip 25 for holding a pen or pencil. The spring members 15 and 16 extend beyond the end of the battery, and the base 21 of the light 3 is provided with a ridge 22 that is adapted to snap between the spring fingers 15 and 16 to hold the light in place. Although only two of the 30 spring fingers are shown, it is understood that any number may be used, and it will be noted that, as the light with the mounting thereof is 35 drawn backward by the clip 20, a contact 23 of the light base will engage the end 24 of the battery and light the light. The light may, therefore, be lighted or extinguished as may be desired.

The case 1 is provided with threads 25 upon 40 which the cap 2 may be threaded as shown, however, it will be understood that a cap of any type or design may be used, and this may be placed on the pen casing in any manner.

45 In the design shown in Figure 1, the pen casing is provided with a small, transparent bead 26

forming a window through which one may see the inner end of the ink reservoir, or the connection 27 thereof to the ink sack, so that one may readily determine when the pen is empty.

It will be understood that changes may be made in the construction without departing from the spirit of the invention. One of which changes may be in the use of other means for providing a transparent section for enclosing the light bulb, another may be in the use of any other means for mounting the bulb at the end of the battery, another may be in the use of any other means for closing a switch to light the bulb, and still another may be in the use of other means for filling the ink sack.

The construction will be readily understood from the foregoing description. In use the device, which is comparatively the same size as a fountain pen, may be used as a fountain pen in the ordinary manner, however, when it is desired to write a note in the dark, the light may be lighted so that the paper upon which one is writing may be illuminated, and, at the same

time, the casing may readily be opened to replace the battery or change any of the parts, and the pen may be filled with ink in the usual manner without opening the casing.

5 Having thus fully described the invention, what I claim as new, and desire to secure by Letters Patent, is:

10 1. A fountain pen having a barrel and a cap, with a transparent point holding section at one end of the barrel and adapted to be covered by the cap when the pen is closed, an ink sack extending substantially throughout the length of the barrel with means feeding ink therefrom to the pen point, a light bulb positioned in the said transparent section at the base of the said pen point, and a battery also extending substantially throughout the length of the barrel and positioned beside the said ink sack.

15 2. A fountain pen as described in claim 1, characterized by a transparent bead forming an inspection opening in the feeding means for determining when the ink supply is exhausted.

20 HERBERT GUDGE.
